UNITED STATES PATENT OFFICE.

HARRY WEARNE, OF RIXHEIM, GERMANY.

DESIGN FOR WALL-PAPER.

SPECIFICATION forming part of Design No. 33,900, dated January 8, 1901.

Application filed December 18, 1900. Serial No. 40,812. Term of patent 7 years.

To all whom it may concern:

Be it known that I, HARRY WEARNE, a subject of the Queen of Great Britain, and a resident of Rixheim, Alsace, Germany, have invented and produced a new and original Design for Wall-Paper, of which the following is a specification, reference being had to the accompanying drawing, forming a part thereof, in which is represented a section of wall-paper embodying the features of my design.

The leading features of my design consist in trellis-figures, upon which the representation of the stalks of a running rose is drawn in such manner as to extend mainly longitudinally of the trellis-figures, flowers appearing in greater abundance at one section of the trellis than at the next section.

The minor features of the design consist in the lozenge shape of the trellis-sections and

in the main stem of the plant passing the 20 lozenge-sections at or near a central point, and finally in the preponderance of foliage at one lozenge-section over that at the next, at which latter section a mass of bloom appears extended to the foliated section. 25

Having thus described my invention, I claim as new and desire to secure by Letters Patent—

The design for wall-paper as herein shown and described. 30

In testimony whereof I have signed my name to this specification in the presence of two subscribing witnesses.

HARRY WEARNE.
